UNITED STATES PATENT OFFICE.

AGOSTINO ROGATI AND LOUIS ARONNE, OF NEW YORK, N. Y.

SOUND-BOX FOR PHONOGRAHS.

1,346,685.

Specification of Letters Patent. Patented July 13, 1920.

Application filed April 26, 1919. Serial No. 292,803.

To all whom it may concern:

Be it known that we, AGOSTINO ROGATI and LOUIS ARONNE, subjects of the King of Italy, and residents of the city of New York, borough of Manhattan, in the county and State of New York, have invented a new and useful Improvement in Sound-Boxes for Phonographs, of which the following is a full, clear, and exact description.

10 This invention relates to talking or sound reproducing machines and has particular reference to sound boxes therefor.

15 Among the objects of the invention is to improve the general construction of sound boxes with respect to the front and rear walls thereof, and the means for connecting the periphery of one wall to that of the other.

20 Another object of the invention is to provide an improved stylus bar with respect to the manner of supporting it in or upon the sound box, the means for securing a needle therein or thereto, and means coöperating with the stylus bar for varying the volume 25 or timbre of the tone produced by the machine.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had 35 to the accompanying drawings, in which like reference characters designate the same parts in the several views, and in which—

40 Figure 1 is a partial front elevation of our improved sound box, parts being broken away to disclose details of construction.

Fig. 2 is a vertical transverse section on the line 2—2 of Fig. 1.

Fig. 3 is a horizontal section on the line 3—3 of Fig. 1; and

45 Fig. 4 is a detail perspective view of the sound regulator.

Referring now more specifically to the drawings we show a sound box comprising front and rear walls 10 and 11 respectively 50 which are illustrated as being of convexo concave form and with circular peripheries. We wish it to be understood, however, that we are not to be limited unnecessarily to the particular shape or construction of such parts. We find for the purpose of these 55 walls that hard rubber, or its equivalent, is

very satisfactory. The means for connecting the side walls to each other through their peripheries comprises a rim 12 of metal or some other suitable rigid material, the 60 same having a threaded seat 13 for connection with the similarly threaded periphery of the plate 10, and having a groove 14 for receiving the periphery of the back plate 11. Otherwise the inner face of the ring or rim 65 12 is substantially smooth and cylindrical for facilitating the insertion of the diaphragm and its holding means. The rear wall is provided with a central hub 15 of any suitable design for attachment to the 70 tone arm connection.

The diaphragm 16 is shown as of any suitable sheet material such as mica, celluloid or metal for which purpose we have found aluminum to be very suitable, and this 75 diaphragm is preferably corrugated concentric with its center leaving a flat rim portion that is gripped between two cushions 17 which likewise are gripped between the periphery of the back disk and filler ring 18 80 adjacent to the periphery of the front disk 10. These several parts being held in proper position by the tightening of the front disk in its seat 13.

The stylus bar 19 is connected as usual at 85 20 to the center of the diaphragm but adjacent to the point of connection it is given a right angular turn in a direction parallel or coincident with the axis of the diaphragm and thence bent again forming a shoulder 90 21 just within but spaced from the inner face of the front disk 10. Thence the stylus bar is directed downward between the disks and is provided with a bearing trunnion 22 having conical bearing points supporting 95 the same at 23 which bearing points are coaxial and arranged within the space between the disks and within the annular rim 12. As a suitable means of constructing the stylus bar and the trunnion support therefor we make the trunnion and a downwardly projecting needle socket 24 of one piece, while the stylus bar proper is projected down into a slot or groove 25 formed in the front face of the trunnion and the 105 socket where it is secured rigidly at 26 as by solder, while the lower end of the stylus 110 constitutes a flexible tongue 27 which co-operating with the lower end portion of the needle socket or chuck serves to hold the needle 28 frictionally in place with sufficient firmness for the practice of the inven-

tion. The needle, however, may be easily withdrawn by the operator's fingers for renewal. Except for the flexibility of the tongue 27 the entire stylus bar and needle 5 chuck are pivoted as shown within the rim 12 for a slight oscillation around the axis of the bearing points 23.

Serving as a guard for the needle chuck and needle and to insure an approximate 10 similarity of appearance between our improvement and the standard sound boxes we provide a thimble 29 loosely surrounding the chuck and needle so as to insure free movement thereof, said thimble being tapped 15 into a hole 30 formed in the lower portion of the rim 12. It will be noted that the use of a set screw is not necessary in this construction and the renewal of needles may be 20 accomplished much more easily and rapidly than when a set screw is used.

A supporting arch 31 of any suitable nature such as a strip of metal is employed beneath the diaphragm rings so as to prevent contact between said rings and the 25 stylus bar. This arch may be supported in place by any suitable means as by attachment to the rear wall or disk 11.

One of the most important features of our 30 improvement consists of the tone regulator which is a device having mechanical connection with some portion of the stylus for modifying the volume and timbre of the tone in a manner somewhat analogous to the action of a mute for a stringed instrument. 35 This regulator comprises a screw 32 tapped into the central portion of the disk 10 oppo-

site the shoulder 21 and having a cushion of resilient material such as rubber 33 carried by the inner end thereof and adapted to be brought into more or less firm contact with 40 said shoulder when the screw 32 is turned by a milled head 34 accessible from the front of the sound box. The regulator may be delicately adjusted by the means indicated so as to make exceedingly fine or delicate 45 variations in tonal effect produced by the instrument. Notwithstanding the fact that the amplitude of the stylus bar is never very great the rotation of the screw through small angles may easily be effected for that 50 degree of adjustment that will produce the control of the oscillations of the stylus bar to produce the desired result.

We claim:

The herein described sound box for talking machines comprising front and rear spaced walls, a rim embracing the peripheries of the disks and serving to hold them in fixed spaced relation to each other, a diaphragm within the space between the walls, 60 cushioning devices gripping the periphery of the diaphragm to hold it in position, a stylus bar connected with the diaphragm and pivoted within the space between the walls, and a supporting arch between the diaphragm securing means and the stylus bar to prevent interference between the diaphragm supporting devices and the stylus bar.

AGOSTINO ROGATI.
LOUIS ARONNE.
